RADIO RECEIVING SYSTEM

Rogers M. Smith, Merchantville, N. J., assignor
to Radio Corporation of America, a corpora-
tion of Delaware

Application June 30, 1933, Serial No. 678,410

23 Claims. (Cl. 250—20)

The present invention relates to radio receiving systems, and more particularly, to radio receiving systems wherein one or more electric discharge devices or electronic tubes are caused to function in a plurality of signal conveying circuits. Such systems are of increasing commercial importance in connection with "midget" radio receivers, automobile receivers and the like, wherein certain definite requirements in regard 5 to size, current consumption and cost must be met.

In automobile receivers, in particular, it is important that current consumption be kept at minimum value while at the same time maintaining a high level of sensitivity. Accordingly, it is desirable to reduce the number of current consuming devices, and in particular, the number of tubes employed in such apparatus without correspondingly reducing the operating efficiency. 15 To this end, a single electric discharge device or vacuum tube may be arranged to function as an element of a plurality of signal conveying circuits.

Radio receiving circuits and the like, wherein 20 an electronic tube performs two functions, as in a reflexed amplifier, are known, as well as circuits wherein further functions are provided, though attended often by undesirable complication of said circuits or of the circuit arrangement. It is conceivable, however, that if a further combination of functions may be given to one vacuum tube, without introducing undesirable circuit complications, the number of tubes necessary for use in a given receiving circuit may 25 be greatly reduced and to good advantage.

It is, therefore, an object of the present invention to provide an improved receiving system embodying a single electric discharge amplifier device wherein a reduction in operating current 30 is effected with increased amplification and wherein said device performs a plurality of functions in separate signal circuits thereof.

It is a further object of the present invention to provide an improved radio receiving system 35 wherein a single multi-element electric discharge device or electronic tube with a single cathode may have a plurality of different functions in a simplified circuit.

A device which is at present preferred is a 40 vacuum tube of the pentode type, having five elements, namely a cathode, a control grid, an anode, and screen and suppressor grids, whereby a greater amplification is obtainable therefrom and, in addition, at least one and preferably two 45 anodes or plates also associated with the cathode,

independently of the other electrodes, for diode rectification of signal currents.

It is a still further object of the present invention to provide a radio receiving system wherein, in a single tube amplifier device of the character above described, the combined functions of high frequency amplification, detection, low frequency amplification, and automatic volume control may be provided through simple circuit means.

In this connection, the present invention is, 10 therefore, particularly adapted for use with superheterodyne type receivers to provide a combined intermediate frequency amplifier-second detector-automatic volume control-audio frequency amplifier system, the vacuum tube amplifier device preferably being of the pentode type. Such a device provides, in an amplifier, a relatively high amplification factor with correspondingly low operating potentials and a stable operating characteristic. The use of such a device 15 and circuit in a battery or automobile receiver results in high gain with an appreciable reduction 20 in the current consumption and battery drain.

The invention, however, is not limited to superheterodyne receivers of the battery type, nor to 25 a second detector circuit of a superheterodyne receiver, but may be applied to any detector circuit which is associated with and interposed between high frequency and low frequency amplifier circuits and in conjunction with automatic 30 volume or gain control means for the system in which the detector is located.

The use of a separate and additional diode plate 35 for supplying control potentials or current to other circuits, such as automatic volume control circuits, may be desirable in certain receiving systems, and accordingly, it is a further object of the present invention to provide an improved circuit of the character above described, wherein a diode rectifier function and an automatic volume control function are separated.

It is a still further object of the present invention to provide a system of the character above described, having an improved control circuit in connection with filter circuits for the two signal bands to be amplified.

In accordance with one embodiment of the invention, a diode detector is supplied with signal energy from the anode or output circuit of a pentode type amplifier, both the detector and amplifier being provided in a single envelope and having a common cathode, and the audio frequency signal output therefrom is reflexed, by resistance or impedance coupling, for example, preferably onto the pentode grid then back 55

through the pentode, and the pentode output circuit, to the utilization system or to a further amplifier, whereby both the control grid and the anode of the pentode serve to carry both high and low frequency signals, suitably filtered input and output circuits being provided for both bands of signals.

The automatic volume control potentials are obtained from the direct current component of the rectified signal current either directly from the detector circuit or indirectly from a separate rectifier circuit in connection with a separate anode, whereby as hereinbefore stated, the device is provided preferably with two diode plates.

15 The invention will, however, be better understood from the following description when taken in connection with the accompanying drawings, and its scope will be pointed out in the appended claims.

20 In the drawings, Fig. 1 is a schematic circuit diagram of a radio receiving system embodying the invention; and

25 Figs. 2, 3 and 4 are similar diagrams of modifications of the system shown in Fig. 1.

30 Referring to Fig. 1, a high frequency amplifier 5 and a low frequency amplifier 6 having an output device 7 provide the usual signal channel of a receiver, with a detector circuit or system 8 therebetween having a plurality of functions in accordance with the invention, and as hereinbefore pointed out.

35 In the present example, a superheterodyne type of receiver is indicated, wherein a radio frequency amplifier device 9 and a combined detector and oscillator device 10 are provided in the high frequency amplifier 5 and connected in customary cascade relation through suitable coupling circuits 11 between a high frequency input or antenna circuit 12 and a high frequency output circuit 13.

40 This apparatus is preferably electrically shielded as indicated by the dotted rectangle enclosure therefor, having a ground lead or base indicated at 14. The ground lead may not necessarily be connected to ground, but represents the low potential lead or circuit connection of the apparatus. A cathode return lead 15 for the two devices 9 and 10 is connected to the ground lead 14 as indicated, and includes a self bias resistor 16. 45 Additional biasing potentials for volume control purposes are supplied to the devices 9 and 10 through a supply lead indicated at 17. This lead includes a high frequency filter provided by suitable series resistors 18 and bypass condensers 19. 50 This circuit connection will further be described hereinafter.

55 An anode potential supply lead also for this portion of the receiver is indicated at 20. For the reason that the construction and circuit arrangement of this portion of the receiver does not concern the present invention, further description is believed to be unnecessary, and for the sake of simplicity and clearness in the drawings, the remainder of the circuits have been omitted.

60 Likewise, the audio frequency amplifier 6 represents any suitable low frequency amplifier having an electric discharge amplifier device or vacuum tube 21 connected between a suitable input circuit 22 and an output circuit 23 leading to the output device 7. Audio or low frequency coupling transformers are indicated at 24 and 25 to provide a cascade connection through the amplifier for signal potentials delivered to the input circuit 22. Since the audio or low frequency amplifier and the output device represent any suitable utiliza-

tion means for the low frequency signals, and do not form part of the present invention, further illustration of the same and a further description are believed to be unnecessary. The amplifier is indicated as being enclosed in a suitable casing or container, by the dotted rectangle 6, and is provided with suitable anode potential supply and return ground leads 26 and 27, respectively.

65 The high frequency output circuit 13, which may be taken as representing any source of high frequency modulated radio signals, is coupled to the circuit 8, which, in turn, is coupled to the low frequency input circuit 22 to complete the signal channel of the receiving system. The modulated signal current, in passing through the circuit 8 between the high frequency signal output circuit 13 and the low frequency signal input circuit 22, is caused to pass through a plurality of transformations, including amplification at high frequency, diode detection, amplification at low frequency, and rectification for providing direct current control potentials for automatic volume control purposes.

70 In providing the several functions in this transformation, a single electric discharge or vacuum tube device 28 is utilized in the circuit 8, such device having a single cathode 29, at least one diode plate or anode 30 and preferably at least one other anode electrode 31, a first or inner grid 32, an output anode 33, a screen or second grid 34, and preferably a third or suppressor grid 35, although such device may function in the circuit of the present example without such suppressor grid. With an indirectly heated cathode in a device as illustrated, a heater element 36 is also provided for the cathode. Such a device will be termed a duplex diode pentode.

75 The cathode 29 is associated with the diode plates 30 and 31 and also with the remaining pentode electrodes or elements 32 and 33. The screen grid 34 serves to decouple, in a well known manner, the last-named triode elements which serve as control grid and anode, respectively.

80 As will hereinafter be seen, a tube of this character provides the advantage that the electron stream of a portion thereof which is utilized as an amplifier may be separated from the electron stream of another portion which provides a diode rectifier, both the amplifier and rectifier being within the same electric discharge device 28 and with the common cathode, thereby permitting separation of the amplifier circuits from the rectifier circuits.

85 The source of high frequency signal potentials, represented by the high frequency output circuit 13, is coupled to the control grid 32 through a high frequency input circuit 37. The input circuit includes a suitable high frequency input impedance or coupling device such as the tuned secondary 38 of a coupling transformer 39. The 90 grid receives a suitable biasing potential through this circuit and through a low potential supply lead 40 therefor, connected to the ground lead 14 through a coupling resistor 41. The biasing potential is supplied from any suitable source such as a self bias resistor 42 in the cathode return lead, indicated at 43. The self biasing resistor 42 is provided with a suitable radio frequency and audio frequency bypass condenser 44 also connected with the ground lead 14. A suitable high frequency bypass for the circuit 37, directly to the cathode lead 43, is provided by a condenser 45.

95 The input circuit 37 is tuned to the frequency of the incoming signal, such as the selected intermediate frequency, and through it, the incoming

signal, usually an audio frequency modulated radio frequency carrier wave, is applied to the control electrode 32.

Intermediate frequency signals delivered to the control grid 32 from the input circuit 37 are amplified and transmitted from the pentode output anode circuit indicated at 46, through a coupling device 47 located therein and a supply lead 48 to at least one, and preferably both, of the diode plates 30 and 31 in parallel as shown.

In the present example, the coupling device 47 is a high or intermediate frequency transformer having a primary 49 in the amplifier output circuit 46 and a secondary 50 connected to the lead 48 in the diode rectifier circuit. The low potential side of the primary is connected to ground through a suitable high frequency bypass condenser 51, and also, to the input circuit 22, through which it is connected to the positive anode supply lead 26, as indicated in the drawings. The last named lead is connected with a main high potential supply lead 52 which is connected with a suitable current supply source or unit 53.

The unit 53 also supplies, through a supply lead 55, all cathode heaters, in the manner indicated by the supply leads 56 connected with the heater 36 of the device 28. Other cathode supply leads are omitted for the sake of simplicity and clearness in the drawings, as hereinbefore pointed out.

The current supply unit 53 is energized from a suitable power source such as a battery 54, in an automobile installation, although any other suitable power source may be utilized with the proper supply means in the unit 53. The battery and the power supply unit 53 connected therewith are grounded as indicated. While the present receiving system shown in Fig. 1 relates particularly to automobile radio receivers, the supply source and battery circuit do not form part of the invention and, therefore, are not believed to require further description.

The low potential side of the secondary 50 of the coupling device 47 is connected, through a resistor 57 having a relatively high resistance value, to the movable contact 58 of a potentiometer device or resistor 59. The potentiometer device is connected between a lead 60 in turn connected with the cathode lead 43 and the cathode, and a lead 61 and a coupling condenser 62. The latter is connected with the lead 40 and the low potential side of the input or grid circuit 37, between the latter and the coupling resistor 41. The leads 60 and 61 are preferably electrically shielded, with the shield connected to ground as indicated by the dotted lines 60' and 61', for the reason that they are usually extended, in use, to a suitable control point for the device 59, in an automobile installation.

From an inspection of the circuit diagram, it will be seen that modulated high frequency signals appearing in the output circuit 46 are amplified because of the high frequency impedance means 47 in circuit therewith and are, through said device, transferred to the rectifier circuit which includes the lead 48 and the diode plates 30 and 31. The modulated signals are then rectified in conjunction with the cathode 29 through the rectifier circuit which may be traced through the cathode lead 43, thence to the lead 60, through the resistor element 59 of the potentiometer device to the movable contact 58 and the lead 63, and through the high resistance element 57

back to the low potential side of the secondary 50 of the high frequency coupling device 47.

The diode rectified signal current flowing in the circuit above outlined comprises both an audio frequency signal component and a direct current component and is applied to the resistance elements in series to set up controlling potentials across the element 57 and any portion of element 59 which may be in circuit therewith. The direct potential is applied to the automatic volume control circuit 17 through a supply lead 64 connected to the resistance element 57 at a suitable point such as its negative end or terminal adjacent to the low potential side of the secondary 50.

Because of the diode rectification, it will be seen that the resulting rectified current will flow in the resistor 57 in the direction of the arrow, whereby a negative potential is applied to the control circuit 17 for the amplifier 5 in response to an applied carrier wave, an increase in the intensity of the latter causing an increased negative control potential to be applied to the preceding amplifiers and a corresponding reduction in the gain therein. The potential drop caused by the flow of rectified signal current through the resistor 57 is thus applied to the amplifier for automatic volume control use and varies in response to changes in the carrier wave intensity.

Because of the nature of the amplifier devices used in modern radio apparatus, a wide range of control potentials is required, and therefore, the voltage available across the rectifier circuit, including the resistor 57, or between the supply lead 64 and the ground lead 14, may be relatively high. For the above reason, the resistor 57 may have a relatively high value, preferably several hundred thousand ohms, with the type of tubes and circuit shown.

This resistor 57 also serves the purpose of stepping down the corresponding audio frequency signal potential to be applied at the contact 58 in order not to overload the grid 32, with an adjustment of the contact 58 for maximum volume.

It will be seen that as the contact 58 is moved to the lower end of the resistor 59, as viewed in the drawings, the contact will be at cathode potential, while as the contact is moved to positions approaching the extreme opposite position, the contact will be decoupled increasingly from the cathode through the introduction of the resistor 59 and will correspondingly increasingly be coupled to the control grid 32.

Audio or low frequency potentials set up across the resistor 59 are conveyed from said resistor through the lead 61, the coupling condenser 62 and the lead 40, to the grid 32 through the circuit 31 which is of low impedance, to audio frequency signals. The impedance of the coupling resistor 41 is of such a value that it offers a relatively high impedance to the audio frequency signal potentials.

Viewed in another aspect, operation of the audio frequency volume control potentiometer, that is, movement of the contact 58 on the potentiometer resistor 59, serves to control the amplitude of the audio frequency component of the signal upon the grid 32, by introducing into the signal rectifier output circuit a larger portion of the resistor 59 which is, at the same time, introduced between the cathode and the control grid of the pentode amplifier. The greater resistance causes a greater potential drop and,

therefore, a higher audio frequency potential on the control grid 32.

A suitable bypass condenser 65 is provided for the high frequency circuit to ground from a point 5 between the resistor 57 and the low potential end of the secondary 50. The screen grid 34 is also supplied with potentials through a supply resistor 66 in connection with the supply lead 52, and the resistor is provided with a suitable bypass capacitor 67 for filtering purposes.

Audio frequency signals placed upon the control grid 32 are amplified and applied to the output anode circuit 46 and find a low impedance path through the high frequency coupling device 15 47 to the input circuit 22 for the audio frequency amplifier 6. The high frequency bypass condenser 51 is of a value which does not offer any appreciable shunt effect for audio frequencies upon the circuit. However, for tone control purposes it may be desirable to provide a bypass capacitor such as that indicated at 68, and a controlling switch 69 in the anode output circuit 46 between ground and the junction of the high and low frequency circuit impedance elements, represented by the coupling elements 47 and 24 in the present example, as indicated. Upon closure of the switch 69 certain higher audio frequency signals may then be bypassed to ground and interference from noise sources eliminated, prior 25 to amplification in the audio frequency amplifier.

The rectified signal current flows through fixed and variable voltage divider resistors 57 and 59, respectively, in the rectifier output circuit, the first of which is utilized as an impedance for supplying automatic volume control potentials to preceding amplifier devices, at a relatively high value for the suppression of strong signals. The rectified audio frequency signal component is reduced through the resistor 57 to such a value 35 that with a maximum incoming signal wave and with the potentiometer volume control contact 58 at the maximum volume position at the upper end of the resistor 59, as viewed in the drawings, the control grid 32 may not then be overloaded 40 appreciably by the audio frequency signal, whereby noticeable distortion may be introduced.

In the present example, and as a preferred arrangement of the circuits, the high frequency signal input circuit 37 is connected with the 50 innermost or first grid of the amplifier device, which is the grid 32 indicated in the drawings. While both of the anodes 30 and 31 of the diode rectifier are connected together and utilized in parallel in the common rectifier circuit, they may, 55 in certain applications, be connected to a common signal input circuit and to separate output circuits for controlling different functions in the receiving system, as will hereinafter be described.

The resistor 41 between the low potential side 60 of the circuit and ground may be relatively high, for example, such as one half megohm, as an audio frequency coupling impedance, while the radio frequency bypass condenser 45 may have a value of substantially 300 micro-microfarads, being in shunt to the grid circuit and therefore being of relatively high impedance to audio frequency signals as is desirable in order not to affect appreciably the audio frequency characteristic of the signal transmission. The resistor 65 70 42 is of sufficient value to provide the desired bias potential on the grid 32, for example, 3 to 6 volts in a preferred device of the type shown, and the bypass capacitor or condenser 44 may have a value of 5 microfarads.

75 It should be noted that the devices 9 and 10

in the input signal circuit of the receiver receive a normal biasing potential from the fixed source provided by the self bias resistor 16 and an additional signal controlled bias potential from the rectifier circuit through the supply lead 5 64, with the resistor 57 as the source.

With the diode rectifier circuit connected to the cathode and with a self bias resistor 42 in circuit with the cathode 29 of the combined detector amplifier device 28, it will be seen that the 10 potential existing in the self bias resistor 42 is applied to the biasing circuits of the devices 9 and 10 in opposition to the bias potential provided by the source 16. Accordingly, in the circuit shown, the source 16 is arranged to provide 15 an additional potential equal to that provided by the source 42, whereby a normal bias is obtained on the devices 9 and 10.

This may more readily be seen by tracing the bias circuit for the device 9 from the input grid 20 circuit thereof, through the circuit 11, resistor 18, circuit lead 17, through the second filter resistor 18 to the lead 64, thence through the impedance or resistor 57, lead 63, the contact 58, a portion of the volume control resistor 59, through 25 the lead 60 to the cathode lead 43. From this point, the circuit may further be traced through the self bias resistor 42 to the ground lead 14, thence through the resistor 16, to the cathodes of the devices 9 and 10. The polarity of the 30 potential existing in the various resistors mentioned is indicated by suitable polarity marks adjacent to the terminals thereof, and in tracing the circuit outlined, it will be seen that a potential existing in the resistor 16 is, in the circuit outlined, in opposition to that existing in the resistor 42.

Attention is now directed to Fig. 2 wherein an electric discharge amplifier and rectifier device 70, of the tetrode or screen grid type is provided 40 with an inner grid 71 connected with a high frequency signal input circuit 72, the low potential side of which is represented by the grid return lead 73.

The main anode is indicated at 80 and is connected with a high frequency anode output circuit 74, which is connected through a high frequency coupling device 75 and a high frequency supply lead 76 with an anode 77 associated with the cathode 78 to provide a diode rectifier. A 50 screen grid 79 is provided between the main anode 80 and the control grid 71.

High or intermediate frequency signals, amplified in the tetrode portion of the device 70, are supplied through the output circuit 74 and the 55 coupling device 75 to the input circuit 76 for the anode 77. The signals are rectified through the diode rectifier provided by the anode 77 and the cathode 78, and pass through an audio frequency and direct current impedance element 81 in the 60 form of a tapped resistor providing a potentiometer, the movable contact of which is indicated at 82.

The rectifier circuit is completed from the resistor 81 to the low potential side 83 of the rectifier circuit, which includes the coupling device 75. This may be a suitable tuned high frequency input transformer as indicated. Any other suitable coupling device, however, may be used in the output anode circuit 74 for coupling the latter to the diode rectifier circuit.

It will be noted that the rectifier or diode circuit returns directly to the cathode 78, whereby the only potentials existing in the rectifier circuit are those caused by the rectification of sig- 75

nals, the signal potentials being available across the impedance element 81. These potentials are variably applied to the inner or control grid 71 through a connection with the variable tap 82 which may be traced through a coupling condenser 86 and a combined coupling and high frequency filter impedance represented by a resistor element 87 between the coupling condenser 86 and the ground lead indicated at 89.

10 The connection for the grid lead 73 is made at a suitable lower potential tap point 88 on the resistor 87 whereby overloading of the grid 71 with audio frequency signals is prevented, when the tap 82 is moved to the extreme audio frequency volume position at the right hand end of the resistor 81, as viewed in the drawings. A bypass condenser 84 from the lead 73 to ground and cathode provides, with the resistor 87, a suitable high frequency filter for the audio frequency 20 or diode rectifier circuit.

Suitable normal operating or biasing potential for the grid 71 is supplied through a portion of the resistor 87 from a self bias resistor 90 in the cathode return lead 99.

25 This circuit is similar to that shown in Fig. 1, except that the audio frequency potentials applied to the inner or control grid 71 are prevented from reaching excessively high values by a fixed ratio established by the tap 88 on the impedance device 87. The audio frequency volume control device is directly connected to the impedance element 81 in the rectifier circuit, and suitable audio frequency potentials for the desired volume are then selected directly therefrom, subject, however, to a fixed reduction ratio in the impedance 30 87. High frequency or intermediate frequency signals are supplied to the input circuit 72 through a suitable input coupling device 91, and the audio frequency output signals are transferred to the output circuit through an audio frequency output device 92 in connection with the output anode circuit 74 for the tetrode, in the same manner as described in connection with the preceding figure. Therefore, further description 35 is not believed to be necessary in connection with these features.

In this circuit modification, the supply of potentials for automatic volume control purposes is obtained from a separate impedance element in 50 a separate diode rectifier circuit provided in connection with the second rectifier anode 93 which, like the anode 77, is directly associated with the cathode 78 outside the electron stream of the tetrode.

55 High frequency or intermediate frequency signals are supplied to the anode 93 from the same circuit 76 as the anode 77 through a coupling condenser 94. The second diode rectifier circuit may be traced through a lead 95 directly connected with the anode 93 and connected to the ground lead 89 through an impedance element or resistor 96, and a control potential supply resistor 97 provided with a shunt radio frequency bypass condenser 98. The diode rectifier circuit 60 is completed through the self bias resistor 90 and a cathode return lead 99 in which this resistor is located. It should be noted that it is desirable to provide a lower impedance at 96 than at 97 in order that the major portion of the 65 potential drop may occur in the resistor 97, and, therefore, be available for control purposes.

70 It will be seen that with this arrangement, the potential existing across the self bias resistor 90 is applied to the anode 93 in opposition to signal 75 potentials impressed thereon by the circuit 76,

whereby a delayed rectifier action is provided. This is for the reason that a positive potential is applied to the cathode 78 because of the potential drop in the resistor 90, and a positive potential is also applied to the anode 93 when rectification occurs on each positive half cycle. Until the positive signal potential on the anode 93 is greater than the positive potential existing on the cathode 78, no rectification can take place.

75 Therefore, the delayed action on the rectifier 10 anode 93 and a delayed automatic volume control of the gain in the preceding amplifier devices is obtained and, as is well known, is desirable in radio receiving systems to permit a certain signal level to be reached before suppression of the gain 15 is initiated.

Automatic volume control leads indicated at 20 100 are connected through suitable filter resistors indicated at 101 to the direct current impedance element 97 for supplying controlling potentials to preceding amplifier devices, in the manner disclosed in Fig. 1. This connection may be made at any suitable point on the element 97 to provide the desired potential for automatic volume control purposes, resulting from rectification of the 25 signal currents. Because 97 is of higher resistance than 96, more D. C. voltage is developed across 97 for automatic volume control purposes, which is desirable in this case.

30 It will be seen that in the embodiment of the invention shown and described in connection with Fig. 2, the detection and automatic volume control functions are separated, but that each rectifier circuit is provided with an impedance element in series with the diode-rectifier therein to set up potentials which in the audio frequency circuit may variably be applied to the control grid of the amplifier portion of the device 70, while in the case of the automatic volume control circuit, 35 the impedance is utilized as a source of variable direct potentials which are responsive to the variations in intensity of the carrier wave to control the gain of preceding amplifier devices.

40 Referring now to Fig. 3, a similar circuit to that shown in Fig. 2 is illustrated, in which a pentode type electric discharge device 102, like the device 28 of Fig. 1, is utilized in place of a tetrode. The cathode is indicated at 140 and the main anode at 141. The diode plate or anode 45 electrodes associated with the cathode are shown at 142 and 143 and the screen grid at 144. The cathode or suppressor grid is shown at 145. A fixed tap connection 103 is provided on the diode rectifier circuit impedance 82a for applying to 50 the control grid indicated at 104, variable audio frequency potentials for further amplification. The impedance 82, with a condenser 85, provides a suitable high frequency filter for the rectifier 55 circuit.

60 The tap connection 103 is connected through a coupling condenser 105 to one end of a volume control potentiometer resistor 106, the other end of which is connected directly to the ground lead 89. The variable volume control tap 107 is 65 connected with a grid lead 108 which, in turn, is connected with the low potential side of the high frequency input circuit 72 and thence to the control grid 104. The lead 108 is provided with a suitable high frequency bypass condenser 109 70 to ground. All other connections are substantially the same as shown in Figs. 1 and 2.

75 It will be noted, however, that in the output circuit 74 the audio frequency coupling element comprises an audio frequency choke coil 109 and 75

an audio frequency coupling condenser 110 which may be utilized instead of a transformer connection in certain receiving apparatus. Also, the coupling device 75 is untuned on the primary 5 side as is desirable in certain receiving circuits.

The operation of the system shown in Fig. 3 is similar to that shown in Figs. 1 and 2. However, the arrangement has the advantage that the audio frequency signals are applied to a 10 potentiometer device 106-107 which is connected directly to ground at one end, whereby as the volume is reduced, the grid approaches or is finally connected to ground, thereby providing a more stable operating circuit.

15 As the volume is increased, the maximum audio frequency signal potentials are applied to the grid 104 when the tap 107 is at the upper end of the resistor 106, as viewed in the drawings. The potentials available at that point are determined by the fixed tap 103 on the signal ratio 20 determining impedance element 82 in the rectifier circuit, the tap being placed at an intermediate point thereon for the purpose of preventing overload of the pentode-grid from audio 25 frequency signals when the volume control device is at a maximum position.

It will be seen that the condenser 109 operates 30 as a compensating tone control, for the reason that the relative impedance between it and the impedance of the potentiometer element 106 varies as the tap 107 is moved along the latter, so that for very low volume adjustments of the tap 107, the shunt impedance of the condenser 109 is 35 relatively high with respect to the portion of the resistance 106 than in circuit between the tap and ground. Accordingly, the signal potentials in the higher audio frequency range are less attenuated as the volume is reduced, which is desirable, as the human ear is less responsive to 40 high frequency sounds at low volume and the high frequency sounds are less attenuated for low volume adjustment than at higher volume adjustments of the volume control device, whereby to the listening ear, the high frequency sounds 45 are maintained at substantially uniform relation to the remainder of the audio frequency range as the volume is reduced. A desired compensated volume control and high frequency bypass arrangement is, therefore, provided in the circuit 50 shown.

In order that the sensitivity of the preceding 55 radio input circuit may be controlled through a variation of the biasing potential applied to the preceding amplifier devices in a receiving circuit such as that shown in Fig. 1, the tap 87 on the automatic volume control supply impedance or resistor 88 may be made variable as indicated. Furthermore, this variable tap may be connected 60 to or ganged with the volume control potentiometer 106 as indicated by the dotted connection 146 and may be provided with a common operating means indicated at 147 whereby the sensitivity of the receiver may be reduced simultaneously with a reduction in volume.

65 In the present example, movement of the potentiometer contact of the device 106 in a downward direction, as viewed in the drawings, causes a reduction of the amplitude of audio frequency 70 potentials applied to the input grid 104. When ganged with the potentiometer or impedance 75 88, simultaneous movement of the contact 87 in the same direction is arranged as shown to cause an increase in the negative biasing potentials supplied to the leads 100, thereby more effectively to

bias the preceding amplifier devices, such as those in Fig. 1, in a direction to reduce the gain there-through.

With an arrangement as above described, an 5 audio frequency volume control potentiometer in the audio frequency rectifier circuit is ganged or connected with a sensitivity control potentiometer in the automatic volume control potential supply 10 circuit and arranged to be operated by a common means simultaneously to control both the 10 audio frequency signal gain through the audio frequency portion of the receiver and the high frequency amplifier gain in the input portion of the receiver.

15 It will be noted that the automatic volume control diode lead 73 is returned, in the circuit of Fig. 3, directly to the cathode lead 99, whereby no delayed automatic volume control action is provided. This may, however, be provided as in Fig. 2, by connection to the ground side of the self bias 20 resistor 97.

A simplified and efficient circuit for combined 25 high frequency amplification, diode signal and diode automatic volume control rectification, audio frequency amplification and automatic volume control operation is shown in Fig. 4, to which 30 attention is now directed.

This circuit may utilize any suitable amplifier-rectifier device. A screen grid tube or tetrode 35 type as shown at 111 is preferred, however, for a simplified circuit, and is provided with a high frequency input circuit 112 connected with the control grid 113, a high frequency output circuit 114 connected with the output anode 115 and with a 40 coupling system 116, to the high frequency lead 117 of the diode input circuit to which both diodes 118-119 are connected in parallel, as in Fig. 1.

The diode circuit coupling device comprises a 45 tuned high frequency choke coil 120 connected in the anode output circuit 114 in series with an 50 audio frequency output coupling resistor 121 provided with an audio frequency output coupling condenser 122, thereby providing a similar output circuit to that shown in Fig. 3.

The high frequency choke coil 120 is connected 55 through a high frequency coupling condenser 123, to a coupling impedance or choke coil 124, in the diode rectifier circuit 117, providing an input device therefor. The two choke coils 124 and 120 are electrically separated by a grounded shield 60 125, whereby electrostatic coupling only is provided between them through the condenser 123. The condenser preferably should have a relatively 65 high impedance to audio frequency signals. This circuit arrangement provides a relatively high selection just preceding the diode rectifier or detector which is desirable for preventing interference in certain radio receiving systems.

The diode rectifier circuit is completed from the 70 cathode, indicated at 127, through a cathode lead 128 directly to the ground lead 129, and from the ground lead 129 through the rectifier circuit impedance 75 130 which, in itself, provides the volume control potentiometer means, and from the opposite end of the potentiometer resistor 130 directly to the low side 131 of the input device 124.

70 Audio frequency signals existing in the diode rectifier circuit and available across the impedance element 130 are controlled in amplitude and applied to the inner or control grid 113 through 75 a grid lead 132 and the high frequency input circuit 112 by the variable tap 133 of the potentiometer device. Movement of the tap 133 serves to control the audio frequency volume as in the preceding embodiments of the invention.

Control potentials for automatic volume control purposes are also derived from the direct potential drop in the impedance element 130 through a suitable connection thereon. In the 5 present example this connection is made normally at the high potential point indicated at 134, and the potentials therefrom are conducted through a lead 135 to automatic volume control leads 136, in which are located suitable filter resistors 137, and 10 across which is connected a suitable bypass capacitor 138, forming with the resistors 137, a filter for the automatic volume control leads.

In the embodiment of the invention shown in Fig. 3, the audio frequency volume control means 15 and a sensitivity control means for a receiving system are shown in ganged relation. In the present embodiment of the invention, the single potentiometer device 130 may be arranged in circuit to control both the audio frequency gain and 20 the bias potential supply for preceding amplifier devices through the medium of a connection with both the input lead 132 for the control grid 113 and the automatic volume control bias supply leads 136.

To this end, a suitable switch, such as a two-way switch 149, is arranged to connect the input ends of the circuit leads 136 alternatively with the potential supply lead 135 or with the lead 132.

In the present arrangement, the switch arm 30 149 is connected through a lead 150 with the input terminal ends of the filter resistors 137 and is arranged to connect with either of two contacts 151 or 152. The contacts are connected respectively with the leads 135 and 132, whereby the 35 D. C. component of the signal potential available across the resistor 130 may be taken in full through the lead 135 or in part as supplied by the contact 133 through the lead 132.

The connection is normally made as indicated, 40 to the lead 135. It will be seen, however, that when connected to contact 152, the biasing potential supplied to leads 136 may simultaneously be varied by operation of the contact 132 along with the audio frequency component of the signal potential taken through the same contact. With 45 this arrangement, combined audio frequency and sensitivity control is provided through a single instrumentality in the form of a simple potentiometer resistor.

It will be noted in connection with the circuit 50 shown and described herein, that the operating bias potential for the control grid 113 is derived wholly from the resistor or impedance element 130 and such bias potentials result only from the 55 reception of a signal and from rectification thereof, so that the control grid is "diode biased" or signal biased and the bias potential automatically increases with increasing signal, and with increased output volume resulting therefrom the 60 adjustment of the volume control tap 133. This arrangement has the advantage that the bias potential applied to the control grid automatically increases with increased signal strength and with an increase in the volume adjustment.

Thus, the system shown in Fig. 4 differs from 65 that shown in the preceding figures, wherein the biasing potentials are derived from a fixed source such as a self bias resistor in the cathode return lead of the amplifier device.

From the foregoing description of the circuit 70 shown in Fig. 4 it will be seen that through the medium of a single variable potentiometer device inserted as an impedance element in a rectifier circuit between a high frequency amplifier input 75 circuit and a low frequency output circuit, in con-

junction with a combined amplifier and rectifier device having a common cathode, combined high frequency amplification, rectified signal and automatic volume control potentials, audio frequency amplification, and simultaneous control of audio frequency and sensitivity control may be obtained, the one potentiometer device serving as a source of both variable and fixed signal and direct current components of the rectified current.

This circuit has the further advantage that 10 the bias potential supplied to all amplifiers, including the audio frequency amplifier, is increased automatically with increase in the signal strength along with the signal potential applied to the 15 audio frequency amplifier, and that no fixed additional source of bias potential is required, thereby simplifying the problem of supplying biasing potentials for the amplifier devices.

This circuit arrangement results in a simplification 20 of the receiving system, a reduction in the number of circuit elements required, and consequently a reduction in the cost of manufacture of apparatus embodying this circuit.

The use of a single electric discharge device for 25 four major functions, including the control of biasing and signal potentials by a single means in a receiving circuit, is of considerable importance in apparatus such as automobile and other battery operated portable receivers where the size of the 30 complete apparatus, the current consumption and cost of said apparatus must necessarily be kept at a minimum.

I claim as my invention:

1. In a radio signal receiving system, the combination 35 with an electric discharge device having a cathode, an anode electrode associated therewith to provide a rectifier, a control grid and a main output anode, of a signal input circuit connected with said control grid, a rectifier circuit for said rectifier connected with said main output anode to receive the signal output therefrom, an impedance network providing coupling means between the rectifier circuit and said input circuit, said network including a fixed and a variable impedance element providing a fixed and a variable potential drop determining means in said network, said variable potential drop determining means comprising a potentiometer having a resistor element and a movable tap thereon, one end of said resistor being connected with the cathode and said movable tap being connected with the fixed impedance element, and means connected between the other end of the resistor element and the control grid for applying signal potentials to said grid.

2. In a radio signal receiving system, the combination 40 with an electric discharge device having a cathode, an anode electrode associated therewith to provide a rectifier, a control grid and a main output anode, of a signal input circuit connected with said control grid, a signal output circuit connected with the main output anode, a rectifier circuit for said rectifier connected with said main output anode, and an impedance network 45 providing a coupling means between the rectifier circuit and said input circuit, said network including a fixed and a variable impedance element providing fixed and variable potential drop determining means in said network, said variable impedance element being connected between the cathode and said control grid and having a movable tap connection with said fixed impedance element.

3. In a signal receiving system, the combina- 50

tion of an electric discharge device comprising amplifier and rectifier elements having a common cathode in a single envelope, a signal input circuit and a signal output circuit for said amplifier 5 element, a variable volume control impedance device in circuit with said rectifier element connected with said input circuit to variably apply rectified signals thereto, a second variable impedance device, circuit means for supplying rectified current therethrough from said rectifier element, an amplifier control circuit connected with said second variable impedance device to receive controlling potentials therefrom, means for simultaneously controlling said variable impedance elements, means for coupling said output circuit to said rectifier element, and means for receiving signals from said output circuit.

4. In a radio signal receiving system, the combination with an electric discharge device having 20 a cathode, an anode electrode associated therewith to provide a rectifier, a control grid and a main output anode, of a signal input circuit connected with the rectifier anode and with the cathode, an impedance element in the last-named connection, means for variably connecting the control grid with said impedance element to supply rectified signal and biasing potentials to said grid from said impedance element, said potentials being thereby simultaneously variable, and an 25 amplifier circuit connected with said impedance element to receive gain controlling potentials therefrom simultaneously variable with said first named potentials.

5. In a signal receiving system, the combination 30 of an electric discharge device comprising amplifier and rectifier elements having a common cathode in a single envelope, signal input and output circuits for said amplifier element, a circuit for controlling the sensitivity of said system, and 35 means for simultaneously varying the control potentials applied to said last named circuit and signal potentials applied to said amplifier element, said means including a variable potentiometer device in circuit with the rectifier element and 40 connected with the signal output circuit.

6. In a radio signal receiving system, the combination with an electric discharge device having 45 a cathode, an anode electrode associated therewith to provide a rectifier, a control grid and a main output anode, of a signal input circuit connected with said rectifier, an impedance network including a variable impedance element, connected in part in circuit with said rectifier and in part between said rectifier circuit and the 50 control grid, whereby said control grid is coupled to said rectifier to receive signals therefrom, the connection with the control grid being direct with said impedance element whereby direct biasing potentials may be received therefrom, a sensitivity control circuit for said system, and means for connecting said circuit with said variable 55 impedance element, whereby control potentials simultaneously variable with said biasing potentials may be applied to said control circuit.

65 7. In a radio signal receiving system, the combination with an electric discharge device having a cathode, an anode electrode associated therewith to provide a rectifier, a control grid and a main output anode, of an impedance network including a variable impedance element, connected between the control grid and the rectifier, and a fixed voltage ratio determining impedance element in circuit with said variable impedance element.

75 8. In a radio signal receiving system, the com-

bination with an electric discharge device having a cathode, an anode electrode associated therewith to provide a rectifier, a control grid and a main output anode, of an impedance network including a variable impedance element, connected between the control grid and the rectifier, a fixed voltage ratio determining impedance element in circuit with said variable impedance element, and means associated therewith in circuit to provide a filter.

9. In a radio signal receiving system, the combination with an electric discharge device having a cathode, a pair of anode electrodes associated therewith, a control grid and a main output anode, of an impedance network including a variable impedance element connected between the control grid and the cathode, a rectifier circuit connected between one rectifier anode element and the cathode through said impedance element, a second rectifier circuit, a second impedance element in said second rectifier circuit with the other rectifier anode electrode, and a control circuit connected with said last-named impedance element to receive a direct current controlling potential therefrom.

10. In a signaling system, an electric discharge amplifier device having a cathode and at least one rectifier plate associated therewith to provide a rectifier, of a signal input circuit for said device, a signal output circuit for said device, 30 high and low frequency impedance means in said output circuit, a signal circuit connected with the low frequency impedance means, a rectifier circuit, including the cathode and one rectifier plate, connected with said high frequency impedance means, impedance means connected in circuit between the cathode and the signal input circuit, a second impedance means connected in said rectifier circuit, means for deriving a potential from said second impedance means, and 35 means for applying a derived potential variably to said first impedance means.

11. In a radio signal transmission circuit, a diode rectifier and an electrical impedance device connected in series therewith, means for supplying high frequency signal potentials to said rectifier, an electronic tube amplifier having a cathode providing one electrode of said rectifier and a control grid connected with said impedance device, a variable impedance network providing said 45 connection, means providing a low frequency separate output circuit for said amplifier, a second diode rectifier having an anode electrode associated with said cathode, circuit means for applying signals to said anode, a low impedance 50 device in circuit adjacent to said anode, and a high impedance device in circuit adjacent to said cathode in series in circuit with said second rectifier circuit, and a control circuit connected with said last-named impedance device to receive direct-current controlling potentials therefrom.

12. In a radio receiving system, the combination with an electric discharge amplifier device having in a common envelope, a cathode, a control electrode, an anode, and at least one additional anode associated with the cathode outside the electron stream of said device, of a high frequency input circuit connected with the control electrode, a high frequency output circuit connected with the first named anode, a rectifier comprising said additional anode and cathode connected with said high frequency output circuit, an output circuit for said rectifier including an impedance element, means providing a connection between said impedance element and the 70 75

control grid, and a low frequency output circuit connected with said first-named anode.

13. In a radio receiving system, the combination with an electric discharge amplifier and rectifier device comprising a cathode, a control electrode, an anode, and at least one auxiliary anode associated with the cathode, of a signal input circuit for said control electrode including a high frequency impedance element, a low frequency impedance element, an output circuit for the first-named anode including a second high frequency impedance element and a second low frequency impedance element, a rectified circuit including said auxiliary anode and the cathode connected with the output circuit through the second named high frequency impedance element, and potentiometer means providing a variable connection between said rectifier circuit and the signal input circuit between the high frequency impedance element and the low frequency impedance element therein.

14. In a radio receiving system, the combination with an electric discharge amplifier and rectifier device comprising a cathode, a control grid, an anode, and at least one auxiliary anode associated with the cathode, a signal input circuit for said control grid including a high frequency impedance element and a low frequency impedance element, an output circuit for the anode including a second high frequency impedance element, and a second low frequency impedance element, a rectifier circuit including the auxiliary anode and the cathode connected with the output anode circuit through the second high frequency impedance element, means providing potential drop producing resistance and a variable potentiometer connection between said rectifier circuit and the input circuit, a high frequency amplifier connected with the first named input circuit, said amplifier having an automatic gain control circuit, and means providing a connection for the last-named circuit with said potential drop producing means for receiving automatic gain controlling potentials therefrom established by a direct current component of the signal current in said rectifier circuit.

15. In a radio receiving system, the combination with an electric discharge amplifier and rectifier device comprising a cathode, a control grid, an anode, and at least one auxiliary anode associated with the cathode, of a signal input circuit for said control grid including a high frequency impedance element, a low frequency impedance element and a source of biasing potential, an output circuit for the anode including a second high frequency impedance element and a second low frequency impedance element, a rectifier circuit including the auxiliary anode and the cathode connected with the output anode circuit through the second high frequency impedance element, and means providing potential drop producing resistance in the rectifier circuit and a variable potentiometer connection between said rectifier circuit and a point on said input circuit between the high frequency impedance element and the low frequency impedance element therein, and said rectifier circuit further including said source of biasing potential so poled that a predetermined fixed positive potential is applied to the cathode with respect to the auxiliary anode in the rectifier circuit, whereby a delayed rectifier action is provided.

16. In a radio receiving system, the combination with an electric discharge amplifier and rectifier device comprising a cathode, a control

grid, an anode, and at least one auxiliary anode associated with the cathode, a signal input circuit for said control grid including a high frequency impedance element, an output circuit for the anode, a rectifier circuit including the auxiliary anode and the cathode connected with said output anode circuit, potential drop producing impedance means in said rectifier circuit, a common circuit lead connecting the input and output circuits with the cathode, and a potentiometer resistor connected between a point on said potential drop producing impedance and said common circuit lead, and having a variable contact connected with the control grid.

17. In a radio receiving system, the combination with an electric discharge amplifier and rectifier device comprising a cathode, a control grid, an anode, and at least one auxiliary anode associated with the cathode, a signal input circuit for said control grid including a high frequency impedance element, an output circuit for the anode, a rectifier circuit including the auxiliary anode and the cathode connection with said output anode circuit, potential drop producing impedance means in said rectifier circuit, a common circuit lead connecting the input and output circuits with the cathode, a potentiometer resistor connected between a point on said potential drop producing impedance and said common circuit lead, and having a variable contact connected with the control grid, and high frequency by-pass means connected between the movable contact of said potentiometer and said common circuit lead.

18. In a radio receiving system, the combination with an electric discharge device having a cathode, a control grid, an anode, and two auxiliary anodes associated with the cathode, of a high frequency signal input circuit having one terminal connected to the control grid and having one terminal connected to the cathode through a potentiometer resistor, a rectifier circuit including said auxiliary anodes and the cathode and said potentiometer resistor, means for supplying amplified high frequency signals to said rectifier circuit whereby said control grid receives direct current potentials for biasing purposes and rectified signal potentials from said potentiometer resistor, an audio frequency output circuit connected with said anode, and a gain control circuit connected with said potentiometer device to receive direct-current controlling potentials therefrom.

19. In a superheterodyne radio receiver for automotive vehicles and the like having a single low voltage source of electrical energy, a combined detector, high frequency amplifier, low frequency amplifier, and automatic volume control system, including in combination, a single electric discharge amplifier device having a cathode and at least one diode plate associated therewith, high frequency and low frequency signal input and output circuits connected with said amplifier device, additional circuit means connecting the diode plate and the cathode between said high frequency input circuit and the low frequency output circuit as a signal rectifier, potential drop producing impedance means in said rectifier circuit, means for variably applying a controlling potential from said impedance means to said amplifier device through said input circuit, an automatic volume control circuit, and means for deriving a second controlling potential from said impedance means for said automatic volume control circuit.

20. In a signalling system, the combination with an electric discharge amplifier and rectifier device having a control electrode, a cathode, an output anode, and at least one diode rectifier 5 anode associated with the cathode, of a rectifier circuit connected between said rectifier anode and the cathode and including a resistor provided with a movable tap, a high frequency signal input circuit connected between said control electrode and the movable tap on said resistor, high frequency coupling means connected between 10 said output anode and the rectifier circuit, an automatic volume control circuit connected with said resistor to receive controlling potentials 15 therefrom, and a separate low frequency output circuit connected with said output anode in series with said high frequency coupling means.

21. In a radio receiving system, a multi-electrode space current device and circuit connections 20 whereby said device functions simultaneously to provide volume control potentials, as a demodulator of incoming signals and as an amplifier of the incoming signals as well as the demodulated signals, said device having electronic amplifier elements and electronic rectifier 25 elements provided with a common cathode, and said circuit connections including signal input and output circuits for said amplifier elements, means for coupling said output circuit to said 30 rectifier elements, an impedance device in circuit with said rectifier elements for producing a potential drop corresponding to the amplitude of received signals and the modulation component thereof, and automatic volume control circuit 35 variably connected with said impedance element, and means for selecting from said impedance element and applying to said amplifier elements a demodulated signal.

22. In a radio signal receiving system, the com-

bination with an electric discharge device having a cathode, an anode electrode associated therewith to provide a rectifier, a control grid and a main output anode, of a signal input circuit connected with said control grid, a rectifier circuit for said rectifier connected with said main output anode to receive the signal output therefrom, and an impedance network providing coupling means between the rectifier circuit and said input circuit, said network including a fixed tapped voltage divider resistor providing a tap connection for said input circuit, means for applying signal potentials across the terminals of said voltage divider resistor and a potentiometer resistor in circuit with said voltage divider resistor for varying the potentials derived therefrom for said input circuit.

23. In a radio signal receiving system, the combination with an electric discharge device having a cathode, an anode electrode associated therewith to provide a rectifier, a control grid and a main output anode, of a signal input circuit connected with said control grid, a rectifier circuit for said rectifier connected with said main output anode to receive the signal output therefrom, an 20 impedance network providing coupling means between the rectifier circuit and said input circuit, said network including a fixed and a variable impedance element providing a fixed and a variable potential drop determining means in said network, a self bias resistor in circuit with the cathode, means for utilizing the potential drop in said resistor to provide a delay potential for said rectifier, and means for utilizing potentials derived from said rectifier above a predetermined delay 25 potential for automatic volume control of said system.

ROGERS M. SMITH.
